UNITED STATES PATENT OFFICE.

LOY H. WALLACE, OF PHOENIX, ARIZONA.

BATTERY-CARD HOLDER.

1,363,545.

Specification of Letters Patent. Patented Dec. 28, 1920.

Application filed July 17, 1919. Serial No. 311,533.

To all whom it may concern:

Be it known that I, Loy H. Wallace, a citizen of the United States, residing at Phoenix, in the county of Maricopa and 5 State of Arizona, have invented certain new and useful Improvements in Battery-Card Holders, of which the following is a specification.

This invention relates to an improved card 10 holder, being particularly designed for use in holding the identification cards of storage batteries whereby the card of each battery may not become separated therefrom.

The invention has as one of its principal 15 objects to provide a holder which may be readily connected to the handle of substantially any conventional type of storage battery and which will be adapted to firmly support a card thereon in such position that 20 a view of the card may be easily had.

The invention has as a further object to provide a device so constructed that a card cannot easily become displaced therefrom.

And the invention has as a still further 25 object to provide a device which will be structurally simple and which may be economically produced.

Other and incidental objects will appear hereinafter. In the drawings:

30 Figure 1 is a perspective view showing my improved device in connection with a conventional type of storage battery,

Fig. 2 is a rear perspective view showing the device in detail, and

35 Fig. 3 is a transverse sectional view taken centrally through the device.

In carrying the invention into effect, I employ an attaching clamp which is formed of companion members 10 and 11 respectively, the lower end portions of these members providing coacting jaws 12. Pivottally connecting these members is a spring 13. The spring is coiled intermediate of its ends and the members are mounted to rock 40 upon the coil. From one end of the coil extends a spring arm 14 provided with a laterally directed terminal 15 seating within a transverse channel in the outer face of the jaw of the member 10. From the opposite 45 end of the coil extends a spring arm 16 provided with a laterally directed terminal 17 seating within a transverse channel in the outer face of the jaw of the member 11. Thus, the spring will act to normally clamp 50 the jaws together while by shifting the upper ends of the members toward each other,

the jaws may be readily separated. The clamp carries a body plate 18. This plate is preferably formed of suitable sheet metal and is oblong in general contour. At its 60 upper margin, the plate is notched in medially to define a lug 19 which is bent over rearwardly about the upper end of the member 10 of the clamp. A second notch is formed in the lower margin of the plate 65 opposite to the first notch to provide a lug 20 which is bent rearwardly about the terminal 15 of the spring arm 14, the lug being curved to seat within the channel of said terminal. Thus, the body plate and clamp 70 are rigidly connected. Secured to the lower margin of the body plate at its rear side are spring arms 21 arranged at opposite sides of the plane of the clamp. These spring arms are bent about the lower edge of the 75 plate and thence extend upwardly to normally engage at their free end portions with the front face of the plate. As shown in the drawings, a length of suitable resilient wire may be employed in forming each of the 80 spring arms, said length of wire being bent to provide spaced parallel strands soldered or otherwise secured at their ends to the rear face of the plate, the strands being looped about the lower edge of the plate. 85

In Fig. 1 of the drawings, I have shown my improved card holder in use upon a conventional type of storage battery 22. As is usual, this battery is provided at its ends with upstanding handles 23. In using my 90 improved device a card, as conventionally shown at 24, is first engaged with the holder, the card being rested against the body plate 18 and held by the spring arms 21. The holder may then, as shown in this figure, 95 be connected to the battery by simply engaging the jaws of the attaching clamp with one of the battery handles. The holder will thus upstand from said handle of the battery to support the card in such 100 position that a view thereof may be easily obtained. The card, of course, carries suitable data identifying the battery. Consequently, at any place, such as a repair shop where a large number of batteries are 105 brought together, a particular battery may be easily located. Furthermore, it will be seen that the spring arms of the holder will support the identifying card thereon in such manner that the card cannot easily become 110 displaced from the holder while the attaching clamp will, in turn, firmly connect the

holder with the battery. Possibility of the loss of the identity of the battery will thus be reduced to a minimum. After the identifying card for a battery has served its

- 5 purpose, the card may be readily slipped from the holder and the holder detached from the battery. I accordingly provide a particularly effective device for the purpose set forth and, as will now be appreciated 10 in view of the preceding description, a device which is, at the same time, of particularly simple construction.

Having thus described the invention, what is claimed as new is:

- 15 1. In a device of the character described, an attaching clamp including companion clamp members, a spring actuating the members, a body plate secured to one of said members and to said spring, and card holding means carried by the plate.
- 20 2. In a device of the character described, an attaching clamp including companion clamp members providing jaws, a spring pivotally connecting said members and acting 25 to normally hold the jaws together, a body plate provided with lugs engaged one with one of said members and the other with said spring for connecting the plate to the clamp, and card holding means carried by the plate.
- 30 3. In a device of the character described, an attaching clamp including companion clamp members providing jaws, a spring

pivottally connecting said members and having spring arms provided with terminals engaging said jaws whereby to normally hold 35 the jaws together, a body plate having spaced lugs formed therefrom, one of said lugs being engaged with the upper end of one of said members and the other of said lugs being engaged with the terminal of one 40 of said spring arms for connecting the body plate to the clamp, and card holding means carried by the plate.

4. In a device of the character described, the combination of a body plate, a clamp secured against one side of the plate and including coacting pivoted spring pressed clamp members one fixed to the plate and the other free for pivotal movement, and a spring arm fixed to the plate and resiliently 50 bearing against the opposite side thereof.

5. In a device of the character described, the combination of a body plate having spaced rearwardly directed lugs formed therefrom, coacting clamp members one 55 seated against the rear side of said plate and engaged at its upper end beneath one of said lugs, and a spring pivotally connecting said members to form an attaching clamp and actuating the members, the spring being engaged by the other of said lugs whereby to connect the clamp to the body plate.

In testimony whereof I affix my signature.
LOY H. WALLACE. [L. s.]
